US00D537836S

(12) United States Design Patent (10) Patent No.: US D537,836 S
(45) Date of Patent: * Mar. 6, 2007

(54) ICON FOR A PORTION OF A DISPLAY SCREEN

(75) Inventors: Paul Gusmorino, Seattle, WA (US); Mark R. Ligameri, Austin, TX (US); Jenny T. Lam, Seattle, WA (US); Greg S. Melander, Redmond, WA (US)

(73) Assignee: Microsoft Corporation, Redmond, WA (US)

() Term: 14 Years

(21) Appl. No.: 29/228,409

(22) Filed: Apr. 22, 2005

(51) LOC (8) Cl. 14-04

(52) U.S. Cl. D14/492

(58) Field of Classification Search D14/485-95; D18/32, 33; D19/6, 1; D20/11; D21/324, D21/329; 715/700-866

See application file for complete search history.

(57) CLAIM

The ornamental design for an icon for a portion of a display screen, as shown and described.

DESCRIPTION

The FIGURE is a front view of an icon for a portion of a display screen showing our new design.

The broken line showing of the region and the unshaded area there within form no part of the claimed design. The broken line showing of a portion of a display screen is for illustrative purposes only and forms no part of the claimed design.
